UNITED STATES PATENT OFFICE.

HORACE FALK NEUMEYER, OF MACUNGIE, PENNSYLVANIA, AND JONAS FRANCIS YOUNG, OF NIAGARA FALLS, NEW YORK.

DESIGN FOR A LAWN-SPRINKLER BODY.

SPECIFICATION forming part of Design No. 26,205, dated October 20, 1896.

Application filed September 8, 1896. Serial No. 605,197. Term of patent 14 years.

To all whom it may concern:

Be it known that we, HORACE FALK NEUMEYER, residing at Macungie, in the county of Lehigh and State of Pennsylvania, and JONAS FRANCIS YOUNG, residing at Niagara Falls, in the county of Niagara and State of New York, citizens of the United States, have invented a new and original Design for a Lawn-Sprinkler Body, of which the following is a specification.

This invention relates to a new and original design for a lawn-sprinkler body; and it has for its object to provide a design of this character that shall be both useful and ornamental.

The leading feature of the design resides in a lawn-sprinkler body having a straight cylindrical portion of a uniform diameter throughout and extended or continued at one end into a conical extension or continuation tapering to a point and annularly contracted intermediate of its point and the straight cylindrical body portion, said sprinkler-body being further provided at one end of the straight cylindrical portion with a cylindrical enlargement having a bell-shaped outer end and at one side of said straight cylindrical portion, between the cylindrical enlargement and the conical extension, with a circular socket projection of a greater diameter than the straight cylindrical portion and having a flat inner side lying next to and extending at both sides of the body.

In the drawings, Figures 1 and 2 are perspective views of a lawn-sprinkler body em-

bodying the herein-described design. Fig. 3 is a side elevation of the sprinkler-body.

Referring to the drawings, the numeral 1 designates a lawn-sprinkler body having a straight cylindrical portion 2. The straight 40 cylindrical portion 2 of the sprinkler-body is extended or continued at one end into a conical extension 3, which tapers to a point 4, and is annularly contracted intermediate of said point and the straight portion 2. The 45 body 1 is further provided at one end of the straight portion 2 with a cylindrical enlargement 5, which is provided with a bell-shaped outer end 6 and oppositely-located parallel annular milled surfaces 7. At one side of 50 the straight cylindrical portion 2, intermediate of the enlargement 5 and the conical extension 3, the body 1 is further provided with a lateral circular socket projection 8 of a greater diameter than the main portion of 55 the body and provided with a flat inner side 9, lying next to and extending at opposite sides of the straight cylindrical portion 2.

What we claim is—

The design for a lawn-sprinkler body herein 60 shown and described.

In testimony that we claim the foregoing as our own we have hereto affixed our signatures in the presence of two witnesses.

HORACE FALK NEUMEYER.
JONAS FRANCIS YOUNG.
